LAMP BASE

Edith Norton, Los Angeles, Calif.

Application October 9, 1950, Serial No. 12,487

Term of patent 14 years

(Cl. D48—20)

To all whom it may concern:

Be it known that I, Edith Norton, a citizen of the United States, residing in Los Angeles, in the county of Los Angeles, State of California, have invented a new, original, and ornamental Design for a Lamp Base, of which the following is a specification, reference being had to the accompanying drawing, forming a part hereof.

Fig. 1 is a front elevational view of a lamp base showing my new design.

Fig. 2 is a side elevational view thereof.

Fig. 3 is a rear elevational view thereof.

Fig. 4 is a top plan view thereof.

The characteristic features of my design are shown in full lines in the drawing.

I claim:

The ornamental design for a lamp base, substantially as shown and described.

EDITH NORTON.
